UNITED STATES PATENT OFFICE.

FREDERICK A. MARSH, OF COLUMBUS, OHIO.

INSUFFLATOR.

Application filed February 18, 1924. Serial No. 693,716.

To all whom it may concern:

Be it known that I, FREDERICK A. MARSH, a citizen of United States, residing at Columbus, in the county of Franklin and State 5 of Ohio, have invented certain new and useful Improvements in Insufflators, of which the following is a full, clear, and exact description.

This invention relates to insufflators, and 10 has for its object to provide a device of this character which will spray or dust powders into the nose, etc., with an efficiency equal to that with which liquids are sprayed by the ordinary atomizer.

15 In spraying liquids the compression of the air bulb causes a partial vacuum in the upper end of the liquid-raising tube, and atmospheric pressure on the surface of the liquid causes the liquid to be raised in the 20 tube and it is then atomized by the air pressure. This method cannot be followed in the use of powder for the reason that atmospheric pressure on the upper surface of the powder is insufficient to discharge the 25 latter, and a stronger pressure would tend to pack the powder and would fail to blow it out of the nozzle in the desired manner.

To overcome the foregoing difficulties, I 30 have devised the present construction in which the air is conducted to a point adjacent the nozzle and therefore acts only on a small portion of the powder at a time.

In the drawings:

Figure 1 is a longitudinal section through 35 the insufflator.

Figure 2 is an end view of the air bulb, and

Figure 3 is a horizontal section taken on line 3—3 of Figure 1.

40 Referring to the drawings more in detail, the numeral 1 indicates a drum or cylinder which may be made of glass or other similar material. Attached to the cylinder at one end thereof is a nozzle 2 which, in this 45 particular instance is shown as curved although it may be of other designs to adapt it to particular purposes. The nozzle is shown as provided with a shoulder 3 against which an end of the drum 1 abuts, and this end of the drum or the nozzle may 50 be roughened if desired in order to more securely connect these parts. Or, the nozzle may be formed integral with the drum by drawing out the end of the latter.

Attached to the opposite end of the drum 55 1 is an air bulb 4 of rubber or the like which has formed thereon a stopper-like protuberance 5. The protuberance 5 is inserted in the end of the drum 1 and the latter may be tapered slightly as indicated by numeral 60 6 in order to form a seat therefor. The head of the stopper 5 is provided with an aperture 7 in which is positioned a glass tube or the like 8. The tube 8 extends longitudinally of the drum 1 to a point adjacent the wall of the nozzle 2 and is adapted to conduct air expelled from the bulb to a point adjacent the mouth of the nozzle. It should be here noted that the position of the tube 8 within the bulb 4 may be varied 65 70 so as to vary the space intervening between the lower end of the tube and the wall of the nozzle, thus regulating the amount of powder dispensed at each operation of the instrument.

75 In operation, it being desired to fill the drum 1 with a powder, it is merely necessary to remove the nozzle 2, place the powder in the drum and return the nozzle to its position on the lower end of the drum. 80 If it is now desired to spray the nose with the powder, the nozzle is placed in the nose, and the bulb 4 squeezed thereby forcing air through the tube 8 to a point adjacent the mouth of the nozzle, thus forcing out a 85 small portion of the powder from the lower part of the apparatus. The removal of pressure from the bulb will cause air to be again drawn into the same and may also draw some small part of the powder into 90 the tube 8. This will not be objectionable, however, as any powder drawn into the tube 8 will be blown out when pressure is again applied to the bulb 4.

95 By this construction it will be apparent that I have devised an insufflator consisting of relatively few parts and one which applies the spraying force at a point adjacent the nozzle mouth thus ejecting the powder in substantially measured quantities. It will also be apparent from the foregoing description that the air is applied adjacent the bottom of the load of powder rather than at the top thereof, thus avoiding the tendency to pack the powder 100 at the bottom of the instrument. While the device is described in connection with medicine in powdered form, it will be under- 105

stood that the same is equally well adapted for use as a distributor for insecticides and the like.

In accordance with the patent statutes, 5 I have described what I now believe to be the best embodiment of the invention, but I do not wish to be understood thereby as limiting myself or the scope of the invention, as many changes and modifications 10 may be made without departing from the spirit of the invention; all such I aim to include in the scope of the appended claims.

Having fully described the invention, what I claim as new and desire to secure by 15 Letters Patent is:

1. An insufflator including a drum, a nozzle on one end of the drum, an air bulb on the opposite end of the drum, and a tube

slidably connected to said air bulb and terminating at a point adjacent the mouth of the nozzle.

2. An insufflator including a drum, a curved nozzle on one end of the drum, an air bulb on the opposite end of the drum, and a tube slidably connected to said air bulb and terminating at a point adjacent the outer convex wall of the nozzle.

3. An insufflator including a drum, a nozzle on one end of the drum, an air bulb including a hollow, apertured protuberance seated in the opposite end of the drum, and a tube slidably mounted in the aperture of said protuberance and terminating at a point adjacent a wall of the nozzle.

FREDERICK A. MARSH.
